UNITED STATES PATENT OFFICE

HENRIK IPSEN, OF BROOKLYN, NEW YORK

TRAY

Application filed August 2, 1929. Serial No. 383,039.

My invention relates to improvements in trays for holding and carrying drinking glasses and the like and it is my object to produce a tray provided with folding handles whereby a number of trays can be stored in a small space when not in use and in which the handles when raised will be rigid so that the liquid in the glasses will not be spilled.

In the drawing Fig. 1 is a top view of my improved tray with the handles raised; Fig. 2 a side view of the structure of Fig. 1; Fig. 3 a view of the structure of Fig. 1 on the line 3—3 thereof; Fig. 4 an end view, partly in section, of the structure of Fig. 1, with the handles folded; and Fig. 5 a detail view of a handle connection.

The tray consists of a base plate 1 and a top plate 2, spaced apart by pillars 3. The top plate 2 is provided with apertures 4, each of which is adapted to hold a drinking glass or the like which passes therethrough and rests on the base plate 1. Parallel slots 5 and 6 are also made in the top plate 2 to receive the carrying handles which pass therethrough.

The carrying handles are in pairs and each is formed of two flat-S-shaped side pieces 7 and 8, connected together by a cross bar or handle proper 9. Lugs 10—10' and 11—11' are secured to the under side of the top plate 2 adjacent the ends of the slots 5 and 6. The bars 7 and 8 are secured to the lugs 10 and 11 and the bars 7' and 8' to the lugs 10' and 11'. The cross bars 9 and 9' are slightly longer than the distance between the side bars 7 and 8 and 7' and 8' so that when the handles are raised they will interlock as best shown in Fig. 3, resulting in a rigid structure which may be carried without slopping the contents of the drinking glasses.

When the trays are not in use the handles are pushed down into the slots and the side bars lie between the plates 1 and 2 as shown in Fig. 4, their length being such that the cross bars 9 and 9' lie within the overall limits of the top plate. The flattened-S-shape of the bars 7, 7', 8, 8' is necessary in order that the handles may lie down flatly on the top plate 2.

Instead of pillars any desired means may

be employed to maintain the base and top plates in spaced relation.

Heretofore such trays have been made with rigid handles which required a large box in packing and shipping and also a large space 55 for storage when not in use. By my invention a theatre, for example, using a large number of such trays may store them in a small space by simply pushing the handles down. In use the handles are raised in interlocked position and the tray is, for all practical purposes as rigid as the old types. My tray may be packed in a smaller box and occupy less space in shipment than the old style tray.

I claim:

1. A tray for drinking glasses and the like comprising a base plate, a top plate provided with apertures adapted to receive drinking glasses and a pair of parallel slots, means for maintaining the plates in spaced relation, a pair of handles each composed of S-shaped side pieces and a cross piece pivotally mounted on the top plate at the slot ends and passing through the slots, substantially as described.

2. A tray for drinking glasses and the like comprising a base plate, a top plate provided with apertures adapted to receive drinking glasses and a pair of parallel slots, means for maintaining the plates in spaced relation, a pair of handles each composed of S-shaped side pieces and a cross piece pivotally mounted on the under side of the top plate at the slot ends and passing through the slots, the side members engaging the cross piece when raised whereby the two handles are interlocked, substantially as described.

In testimony whereof I have hereunto subscribed my name.

HENRIK IPSEN.
